STENCIL PRINTING APPARATUS

John B. Thomas, Watertown, Conn., assignor to
 Roto-Matic Screen Printer, Ltd., New York,
 N.Y., a corporation of New York

Application April 19, 1951, Serial No. 221,794

21 Claims. (Cl. 101—123)

1

This invention relates to an apparatus for printing sheets, such as textile fabric webs, plastic films and paper, with the aid of a stencil. For simplicity, such apparatus will be referred to hereinafter simply as a "silk screen printing machine," it being understood that this term merely is a trade designation for a stencil printing machine and does not indicate that the stencil necessarily is of silk.

It is an object of the invention to provide a power driven silk screen printing machine in which a scraper rapidly moves back and forth across the screen reverses and stops smoothly and quietly.

More specifically, it is an object of the invention to provide a machine of the character described in which the scraper is slowed down prior to reversal or stopping by the provision of a variable speed transmission in the kinematic drive for the scraper and by sharply increasing the speed reduction just before the scraper reverses or stops.

It is another object of the invention to provide an apparatus of the character described in which adjustments in the length of stroke of the scraper can be made easily and rapidly.

It is another object of the invention to provide a machine of the character described which employs far fewer parts on the table top than a present day power driven silk screen printing machine.

It is another object of the invention to provide an apparatus of the character described in which either the point of stopping or reversal of the scraper can be adjusted at will to conform to a web of any width or position.

It is another object of the invention to provide an apparatus of the character described which is of such construction that the scraper drive is automatically cut out at any point of scraper travel without damaging the apparatus.

In the latter connection it is a more specific object of the invention to provide an apparatus of the character described in which the scraper drive is automatically cut out if the screen frame is raised so that there is no danger of having the screen torn.

It is another object of the invention to provide an apparatus of the character described which is of rugged and durable construction.

Other objects of the invention will in part be obvious and in part will be pointed out herein-after.

The invention accordingly consists in the features of construction, combinations of elements and arrangements of parts which will be exempli-

2

fied in the machine hereinafter described and of which the scope of application will be indicated in the appended claims.

In the accompanying drawings, in which is shown one of the various possible embodiments of this invention,

Fig. 1 is a top plan view of a power driven silk screen printing machine constructed in accordance with the present invention and having many details that are shown elsewhere omitted in order to prevent confusion;

Fig. 2 is an enlarged fragmentary view taken substantially along the line of 2—2 of Fig. 1 and is illustrative of the kinematic drive for the scraper;

Fig. 2a is a schematic diagram of a hydraulic transmission unit in said kinematic drive;

Fig. 3 is a sectional view taken substantially along the line 3—3 of Fig. 2;

Fig. 4 is an enlarged fragmentary view taken along the line 4—4 of Fig. 1 and is illustrative of the mechanisms for stopping and starting the scraper upon rise and fall of the stencil screen;

Fig. 5 is a sectional view taken along the line of 5—5 of Fig. 4;

Fig. 6 is a sectional view taken substantially along the line 6—6 of Fig. 3; and

Fig. 7 is a wiring diagram of the circuit for the scraper control mechanism.

In general, the various objects of the present invention are achieved by providing a silk screen printing machine in which the scraper is actuated from an electric motor through a hydraulic transmission. A member is included which duplicates in miniature the movement of the scraper and which functions as a control for reversing or stopping the electric motor. The hydraulic transmission enables the scraper to be rapidly accelerated and decelerated immediately before and after reversal or stopping of the scraper. Thus, there is provided a power drive for the scraper which is both efficient and quiet and which can be adjusted rapidly and with ease.

Referring now in detail to the drawings, the reference numeral 10 denotes a silk screen printing machine embodying the invention and comprising a suitable printing table 12 to either side of which a supply or a take-up reel (not shown) is disposed. The printing table includes a front apron 14 and a rear apron 16 suitably interconnected by struts (not shown).

Attached to the rear apron are a pair of spaced casings 18 (see Figs. 1 and 2) in a side wall of each of which aligned horizontal axles 55 20 are journaled. Each of said axles has af-

fixed to it a sprocket 22 about which a chain 24 is trained. Moreover, each axle 22 turns a second sprocket 26 about which a chain 28 is trained. The two chains 28 engage sprockets 30 which are secured to aligned horizontal axles 32 journaled in the casings above the axles 22. Turning with each axle 32 is another sprocket 34. Each sprocket 34 engages a different chain 36 having an upper flight 38 and a lower flight 40. Said flights extend forwardly through openings 42, 44 in the front wall of each casing 18. A pair of hollow tubular rails 46, 48 are attached to the front wall of each casing in line with the openings 42, 44, said rails serving to enclose the flights of the chains 36. At the forward end of each said pair of rails there is fixed a housing 50 in which there is contained an idler sprocket (not shown) about which the associated chain 36 is trained. The housings 50 are connected by a cross bar 52 which serves to tie together the scraper supporting frame elements on opposite sides of the machine.

The machine 10 includes a scraper 54 of suitable construction designed to ride back and forth across a stencil screen and to clear the pool of ink at both ends of its travel. One satisfactory form of scraper is that shown in the co-pending application of John B. Thomas and Courtney E. Moorhouse, Serial No. 726,504 for Stencil Printing Apparatus, filed February 5, 1947; another acceptable form of scraper is the one shown in co-pending application Serial No. 221,793 for Stencil Printing Apparatus filed simultaneously with the present application, both said applications being assigned to the assignee of the present application.

Essentially, the scraper includes a blade 56 whose opposite ends are mounted on carriages 58 having wheels 60, 62 located between and riding on the rails 46, 48 at opposite sides of the machine. Each carriage is secured by a fitting 64 to the upper flight 38 of its associated chain 36 so that as the chains move back and forth the scraper will be moved in like fashion. The fitting 64 rides in a slot 66 at the bottom of the upper rail 46.

The machine 10 includes a conventional stencil screen 68 secured to a rectangular screen frame 70. The frame is supported between a front bar 72 and a rear bar 74, the mechanisms used to connect the frame and bars being of any suitable construction and desirably being such as shown, described and claimed in co-pending application Serial No. 726,504 for permitting fine adjustments of the position of the frame. Heretofore, only the front support for a stencil screen frame customarily has been adjustable to accommodate frames of different lengths in a direction from front to back of the machine. However, in accordance with the present invention, both bars 72, 74 are adjustable for movement toward and away from the front and back of the machine. Thus, the bar 74 carries at its opposite ends a pair of brackets 76 including clamp portions which are adapted to grip the lower rails 48 on opposite sides of the scraper. The clamp portions are operated by nuts 78 so that the rear bar 72 can be adjustably set at any point along the lower rails. The front bar 72 is similarly equipped with clamp portions so that it too can have its position varied as desired.

To supply the power for reciprocating the scraper, each chain 24 is trained about a sprocket 30 fixed to a countershaft 82 located at the

rear of the machine beneath the table. Said countershaft spans the distance between the two sets of rails 46, 48 and carries two sprockets 30, one for driving each set of chains 24. Secured to the countershaft 82 is a sprocket 84 which is engaged by a chain 86 that is turned by a sprocket 88.

In accordance with a principal feature of the instant invention, the sprocket 88 is mounted on the output shaft 90 of a hydraulic transmission unit 92, i. e. a hydraulic unit capable of effecting speed conversion. Said unit includes in its output section a fluid motor M (Fig. 2a) of any conventional type, such far example, as that shown in Lesson 47 of the manual entitled the "Hydraulics," published by the Henry Ford Trade School of Dearborn, Michigan, bearing copyright 1941 and reprinted in 1950. This type of motor consists of two gears similar to an ordinary gear pump. But, unlike an ordinary gear pump, the body of the motor has a pair of passageways leading from the exhaust port to ports diametrically opposite the exhaust port. The body also has another pair of passageways leading from the inlet port to ports diametrically opposite to the inlet port. This type of fluid motor will deliver rotary power in either direction of rotation at all speeds within its rated limits. The motor is capable of extremely rapid acceleration and deceleration, and can be started, stopped, and even stalled repeatedly without damage.

The input section of the unit 92 constitutes a variable delivery pump P, such for example, that shown at Lesson 15 of said manual, the same being a piston type pump with a stroke which is varied by a change in inclination of a wobble plate. Said pump, when turned at a uniform speed, is capable of varying its delivery in accordance with the position of a control member which regulates the inclination of said plate. The delivery of the pump is connected to the intake of the fluid motor, and the outlet of the fluid motor is connected to the inlet of the pump, thereby forming a closed hydraulic circuit (see Fig. 2a).

The pump is driven by a sheave 94 on the input shaft 96 of the hydraulic transmission unit, and the delivery of the pump is regulated by a control member 98 secured to a shaft 100, whose angular position determines the inclination of the wobble plate and thereby the rate of delivery of the pump.

The control member is biased in a counter-clockwise direction, as viewed in Fig. 2, by a tension spring 102. When this member is in its extreme counter-clockwise position, as viewed in said figure, the wobble plate is positioned to obtain a maximum piston stroke and, hence, maximum delivery of the hydraulic fluid. Moving the control member against the spring 102 in a clockwise direction, as viewed in Fig. 2, lessens the delivery of the pump and consequently reduces the speed of rotation of the hydraulic motor M. Due to the extremely rapid response of this type of motor to fluctuations in the rate of delivery of hydraulic fluid to it, the output speed of the hydraulic transmission unit follows substantially instantaneously any variation in position of the control member 98.

A belt 104 trained around the sheave 94 is driven by a pulley 106. Said pulley is turned by an electric motor 108 through a fluid clutch 110 of any suitable type that will permit the motor 108 to be reversed rapidly, or to assume rapidly

a load, without stalling, burning out the motor, or imposing an unduly high surge of current in the motor supply. A mercury clutch is suitable for this purpose.

The countershaft 82 fixedly carries a male threaded sleeve 112 which meshes with a tapped collar 114, so that said collar will duplicate in miniature the motion of the scraper. It will be observed that, in order for the movement of the collar to be a faithful reproduction of the scraper movement, the kinematic train between the counter-shaft 82 and the opposite ends of the scraper should entirely constitute positive (non-slipping) motion transmitting mechanisms, such, for example, as the chains and sprockets 39, 24, 22, 26, 28, 30, 34, 36 heretofore described. Moreover, in order that the scraper be capable of as rapid an acceleration, deceleration and reversal as the hydraulic motor M, a positive motion transmitting mechanism, such as the chain 86 and sprockets 84, 88, is employed to connect the output of the hydraulic transmission unit to the countershaft. Since slight variations in the rate at which the hydraulic pump P is driven will not noticeably affect the operation of the machine, the drive from the clutch 110 to the hydraulic transmission unit can be effected by sheaves and a belt. This latter connection, moreover, has the advantage of easing the load on the motor and power supply at times of reversal and sudden acceleration.

The collar 114 is secured to a yoke 116 having a pair of depending arms 118, 120 located on opposite sides of the regulating shaft 100. The arm 118 supports a stud 122 extending in a direction parallel to the shaft 82 and having its head facing the opposite arm 120. The stud is threadedly received in the arm 118 to permit adjustment thereof and it is held in any adjusted position by a lock nut 124. Said stud is horizontally aligned with a roller 125 carried by an erect ear 126 on the control member 98.

The other arm 120 mounts a stud 128 similar to the stud 122, but having its head facing in the opposite direction. The stud 128 cooperates with a roller 130 horizontally aligned therewith and mounted on a pendant ear 131 on the control member 98.

From the foregoing, it will be apparent that, when either stud contacts its associated roller, the control member 98 will be rotated in a clockwise direction, as viewed in Fig. 2, to decelerate the output shaft 90 of the hydraulic transmission unit. Moreover, as soon as either stud disengages its associated roller, the control member will be turned in a counterclockwise direction, as viewed in Fig. 2, by the tension spring 162. Movement of the control member in the latter direction is limited by abutment of said member against a vertically adjustable stop 132. The position of said stop is set in accordance with the speed at which the scraper is desired to traverse the screen 68 during the major portion of its travel.

The yoke 116 also carries an extension 134 on which there are mounted a pair of horizontal threaded studs 136, 138. These studs, like the studs 122, 128, are adjustably supported on the yoke. The studs 136, 138 face in opposite directions and may be disaligned, although they preferably are parallel. The upper stud 136 is horizontally aligned with an actuating element 140 of a momentary electric switch 142. This switch is of the two pole single throw type having one normally open and one normally closed pair of contacts which later will be described in

detail. The lower stud 138 is horizontally aligned with the actuating element 144 of another momentary electric switch 146 that likewise is of the two pole single throw type having one normally open and one normally closed pair of contacts. The switch 142 is the one which is actuated by the stud 136 at the time that the scraper is to be brought to a stop at the rear of the machine, and hence, this switch will be referred to hereinafter as the "stop" switch. The switch 146 is engaged by the stud 138 when the scraper is to be reversed at the front of the machine and hence, said switch will be referred to hereinafter as the "reverse" switch.

The stop and reverse switches are mounted on a stationary panel 148 and are connected by suitable wiring in a control circuit soon to be described for the electric motor 108.

The yoke 116 is prevented from rotating by a guide spindle 150 secured to the stationary base 151 of the hydraulic transmission unit. Said spindle is slidable in a bore 152 near the tip of the yoke arm 120.

The axles 20 extend from the casings 18 in which they are journaled and secured in brackets 154 located alongside said casings. Hence, the scraper support, constituting the casings 18, the two pairs of upper and lower rails 46, 48, the housings 50, and the crossbar 52, pivots about the aligned axles 20 at the rear of the machine. Pivotal movement of the scraper support will raise or lower the scraper with respect to the printing table 12, and, since the stencil screen also is carried by the same frame through the medium of the bars 72, 74, will raise and lower the stencil. Thus, the instant machine eliminates the dual supports heretofore independently employed for mounting the scraper and the stencil.

The lower side of the crossbar 52 is engaged by a follower 156 (see Figs. 4 and 5) consisting of a roller 158 horizontally journaled on a shaft 160 carried between the arms of a yoke 162. Said yoke is secured on the upper end of a shaft 164 slidably mounted for vertical movement in a bushing 166 fixed to the front apron 14. The bushing carries a guide bolt 168 having a dog tip 170 slidable in an axial slot 172 in the shaft 164 to prevent rotation thereof.

The lower end of the shaft fixedly supports a block 174 having a pin 176. A similar pin 178 is carried by the bushing 166, said pins having stretched between them a tension spring 180 that biases the shaft 164 upwardly.

One side edge of the block 174 is fashioned into a face cam 182 designed to engage a roller actuating element (not shown) of a momentary electric safety stop switch 184 that is carried by a post 186 depending from the front apron 14, said switch being of the single throw, double pole type, including two pairs of normally closed contacts. The cam 182 actuates the switch 184 when the crossbar 52 is raised from its printing position shown in Figs. 4 and 5.

The post 186 also mounts a momentary electric starting switch 188, this being of the single throw, single pole type, but including a pair of normally open contacts. The switch 188 has a roller actuating element 190 which, in Fig. 4, conceals the roller actuating element for the switch 184. The element 190 is operated by a lever 192 pivotally mounted by a post 194 on the block 174. The lever is eccentrically disposed with respect to the post 194 so that the operative short end of the lever is biased in a counterclockwise direction, as viewed in Fig. 4. A stop

pin 195 limits counterclockwise rotation of the lever with the same horizontally disposed. It will be seen that, with this arrangement, movement of the shaft 164 toward its uppermost position will not operate the switch 188 since the operative tip of the lever 192 will be cammed downwardly by the roller 190 as the shaft moves up, until said tip clears the roller. However, when the shaft 164 moves downwardly from its uppermost position, the operative tip of the lever cannot cam past the roller 190 inasmuch as rotation of the lever is prevented by the pin 195 so that upon such downward movement, the lever 192 forces the roller 190 toward the switch 188 and closes the normally open contacts thereof.

A suitable electric circuit is provided for operating the motor 108, said circuit being illustrated in Fig. 7. The motor derives electric power from three-phase busses 196, 198, 200, only one phase 196—198 of which is employed for the purpose of controlling the motor.

Normally, the machine is idle, that is, the scraper is at rest at the rear of the machine with the upper switching stud 136 engaging the actuating element 140 in the position of the collar 114 corresponding to said position of the scraper.

The machine is started by lowering the scraper mount. This causes the shaft 164 to be depressed and the lever 192 to actuate the starting switch 188. Actuation of said switch is designed to energize the solenoid 202 of a forward operating motor relay 204 which controls four normally open sets of contacts 206, 198, 210, 212. The energizing circuit for the solenoid 202 extends from the bus 196 to the bus 198 running through a wire 214, the momentarily closed but normally open pair of contacts 216 of the starting switch 188, a wire 218, a pair of normally open contacts 220 of the stop switch 142 which, however, now are closed because the scraper is at the rear of the machine and the collar 114, accordingly, is in engagement with the actuating element 140 of said switch, a wire 222, the solenoid 202, a wire 224, a pair of normally closed contacts 226 of the reverse switch 146, a wire 228, a pair of normally closed contacts 229 of the safety stop switch 184, a wire 230, a pair of normally closed contacts 231 of an emergency momentary stop switch 232 (see also Fig. 1) and a wire 233. As soon as the solenoid 202 is energized, it draws up and closes all the contacts of the relay 204.

Closing the pair of contacts 206 completes a holding or "stick" circuit for the forward operating relay 204 as follows: from the bus 196 through a wire 234, the pair of closed contacts 206, a wire 236, the wire 222, the solenoid 202, the wire 224, the pair of closed contacts 226, the wire 228, the pair of closed contacts 229, the wire 230, the pair of closed contacts 231, and the wire 233 to bus 198, so that when the switch 142 is released, the relay 204 will remain energized.

Closing the contacts 208, 210, 212 connects the bus 196 to a motor terminal 238 through the wire 234, the pair of closed contacts 208 and a wire 240; the bus 198 to a motor terminal 242 through a wire 244, the pair of closed contacts 212 and a wire 246; and the bus 200 to third motor terminal 248 through a wire 250, the pair of closed contacts 210 and a wire 252. The connections are such as to turn the motor over in a proper direction to drive the variable delivery fluid pump P in the correct sense to rotate the fluid motor M in such fashion that the scraper is driven toward the front of the machine.

5 The field 254 of the motor is energized throughout working hours, the conventional connections therefor being omitted to simplify the drawings. It thus will be seen that as soon as the scraper support is lowered the starting switch 188 will be closed and the motor 108 will start to move the scraper from the rear to the front of the machine, the scraper continuing to move even after the actuating tip of the lever 192 has passed the roller 190 and permitted the switch 188 to reopen.

10 At the time the scraper starts, the roller 130 on the control member 98 is engaged by the lower speed control stud 128. Accordingly, the scraper starts up slowly. But as soon as the 15 scraper has moved a short distance and the collar 114 has experienced a corresponding movement, the stud 128 is backed off and the control member shifted by the spring 102 into abutment with the stop 132. As this occurs, the 20 scraper speeds up rapidly, it being observed that the roller 130 is quite close to the shaft 100 which the control member turns so that after a very short movement of the scraper the hydraulic transmission unit is set at its top adjusted speed.

25 When the scraper nears the front of the machine, the upper speed control stud 122 will contact the roller 126 to slow down the rate of delivery of the fluid pump P, and thus the rate of speed of the hydraulic motor M, so that very shortly before the scraper reaches the forward limit of its travel, it is rapidly decelerated. This deceleration does not require absorption of the momentum of the scraper and its affiliated parts by buffers, brakes, or the like mechanical power absorption mechanisms which create noise and shock. In the present construction the momentum is absorbed by the hydraulic transmission unit, the same being transmitted from the scraper to said unit in a positive fashion by the divers chains and sprockets.

30 Very shortly after the upper speed control stud 122 has caused the scraper to be slowed down, the lower switching stud 138 engages the 35 actuating element 144 of the reverse switch 146. As this occurs, the pair of contacts 226 of said switch 146 open, deenergizing the holding circuit for relay 204 and thereupon terminating rotation of the electric motor 108 in the direction which causes the scraper to move forwardly.

35 At the same time, the normally open pair of contacts 256 of the reverse switch close, thereupon completing a circuit from the bus 196 through a wire 258, said pair of closed contacts 256, a wire 260, a wire 262, a solenoid 264 of a reverse operating motor relay 266, a pair of normally closed contacts 268 of the stop switch 142, a wire 270, the wire 228, the pair of normally closed contacts 229 of the safety stop switch 184, 40 the wire 230, the normally closed contacts 231 of the emergency stop switch 232, and the wire 233 to the bus 198 so as to energize the relay 266.

45 The reverse operating relay 266 controls four pair of normally open contacts 272, 274, 276, 278. The first pair of contacts 272 functions as the holding means for the reverse relay. When these contacts 272 are closed, a stick circuit is energized for the solenoid 264. Said circuit extends from the bus 198 through the 50 wire 233, the closed pair of contacts 231, the wire 230, the closed pair of contacts 229, the wire 228, the wire 270, the closed pair of contacts 268, the solenoid 264, the wire 262, the wire 260, the closed pair of contacts 272, a wire 55 280, and the wire 258 to the bus 196.

Closing the contacts 274, 276 and 278 reverses one phase of the power supply to the three-phase motor 108. That is to say, the bus 200 still will be connected to motor terminal 248, although through the contacts 276 of the reverse operating motor relay, rather than through contacts 210 of the forward operating motor relay. However, the bus 196, instead of being connected to motor terminal 238, now will be connected to motor terminal 242 through contacts 274 of the reverse operating motor relay; and the bus 198, instead of being connected to motor terminal 242, now will be connected to motor terminal 238 through contacts 278 of the reverse operating motor relay. As soon as the direction of travel of the motor is reversed, the scraper will start to move back toward the rear of the machine; and, in so doing, first will cause the speed of the hydraulic motor, and hence the scraper, to be rapidly accelerated; this being caused by disengagement of the stud 122 and roller 126.

When the scraper nears the rear of the machine, the speed thereof is decelerated rapidly upon engagement of the stud 128 and the roller 130. Very shortly thereafter the stud 136 will engage the actuating element 140 of stop switch 142, to thereupon open the pair of contacts 268 which deenergizes the stock circuit for the solenoid 264 so that the motor 108 is rendered ineffective.

Thus the scraper will stop at the rear of the machine. If it is desired to have the scraper run through another cycle, a pair of normally open contacts 281 of a momentary repeating switch 282 are closed, these contacts being connected in shunt with the contacts 216 so that closure thereof will repeat the cycle hereinabove described.

If, at any time during a cycle, the rail assembly carrying the stencil frame should be raised, either accidentally or otherwise, all motor control circuits from the bus 198 immediately are opened, so that the motor 108 is stopped. The scraper also is stopped.

It is desirable for the scraper to be brought to a quick stop so that if the screen should be raised rapidly the scraper will not tear the same. To this end, I provide a brake 284 on the countershaft 82, said brake being a solenoid brake of any conventional type, for example, one such as shown and described in detail in application Ser. No. 726,504. The brake has a pair of shoes which are designed to engage a drum mounted to turn with the countershaft. A spring biases the shoes into engagement with the drum, and a solenoid 286 (Fig. 7) when energized holds the shoes apart. The solenoid is connected by a lead wire 288 to the bus 200 and by a lead wire 290 to a pair of normally closed contacts 292 of the switch 184. Another lead wire 294 runs from said contacts to the bus 198. Thus as long as the switch 184 is idle (the crossbar 52 is down) the solenoid will be energized and the countershaft 82 free. But as soon as the rail assembly carrying the stencil frame is raised and the switch 184 actuated to stop the motor, the solenoid will be deenergized permitting the spring to brake the rapidly moving scraper.

It thus will be seen that there is provided a machine which achieves the several objects of this invention and is well adapted to meet the conditions of practical use.

As various possible embodiments might be made of the above invention, and as various changes might be made in the embodiment above set

forth, it is to be understood that all matter herein described or shown in the accompanying drawings is to be interpreted as illustrative and not in a limiting sense.

Having thus described the invention, there is claimed as new and desired to be secured by Letters Patent:

1. In a silk screen printing machine having a printing table, a scraper, a track guiding said scraper for movement back and forth across said table, an element, means to mount said element for reciprocation, a positive kinematic train interconnecting said scraper and said element, said train including a motion reducing mechanism whereby said element duplicates in miniature the movement of the scraper, a reversible electric motor, a hydraulic speed-varying transmission unit driven by the electric motor, a control member regulating the output speed of the unit, means to drive the scraper from the unit, a control circuit for said electric motor, a starting switch, and switches for governing the operation of said motor, said last named switches and said control member being so disposed for actuation by said element that upon actuation of said starting switch said scraper will start at slow speed from the rear of the machine, rapidly accelerate, subsequently rapidly decelerate as it approaches the front of the machine, reverse at the front of the machine, slowly start to the rear of the machine, rapidly accelerate, subsequently rapidly decelerate as it approaches the rear of the machine, and finally stop as it reaches the rear of the machine.

2. In a silk screen printing machine having a printing table, a scraper, a track guiding said scraper for movement back and forth across said table, an element, means to mount said element for reciprocation, a positive kinematic train interconnecting said scraper and said element, said train including a motion reducing mechanism whereby said element duplicates in miniature the movement of the scraper, a reversible electric motor driving said scraper, switches actuated by said element for reversing the motor when the scraper reaches the front of the machine and stopping the motor when the scraper reaches the rear of the machine, and a starting switch.

3. In a silk screen printing machine having a printing table, a scraper, a track guiding said scraper for movement back and forth across said table, a reversible electric motor, means governed by the position of the scraper to reverse the electric motor when the scraper reaches the front of the machine and to stop the electric motor when the scraper reaches the rear of the machine, means to start the scraper toward the front of the machine from the rear of the machine, a hydraulic speed-varying transmission unit driven by the electric motor, a control member regulating the output speed of the unit, means to drive the scraper from the unit, means governed by the position of the scraper and actuating the control member so as to set the unit at a low output speed when the scraper is starting from the front or back of the machine, to thereafter rapidly accelerate the output speed of the unit, and to rapidly decelerate the output speed of the unit as the scraper approaches the front or rear of the machine.

4. In a silk screen printing machine having a printing table, a scraper, a track guiding said scraper for movement back and forth across said table, a rotary shaft, means to turn said shaft in opposite directions, means governed by the position of the scraper to reverse the rotation of

11

the shaft when the scraper reaches the front of the machine and to stop the shaft when the scraper reaches the rear of the machine, means to start the scraper toward the front of the machine from the rear of the machine, a hydraulic speed-varying transmission unit for driving the shaft, a control member regulating the output speed of the unit, means to drive the scraper from the unit, means governed by the position of the scraper and actuating the control member so as to set the unit at a low output speed when the scraper is starting from the front or back of the machine, to thereafter rapidly accelerate the output speed of the unit, and to rapidly decelerate the output speed of the unit as the scraper approaches the front or rear of the machine.

5. In a silk screen printing machine having a printing table, a scraper, a track guiding said scraper for movement back and forth across said table, a rotary shaft, means to turn said shaft in opposite directions, means governed by the position of the scraper to reverse the rotation of the shaft when the scraper reaches one end of the machine and to stop the shaft when the scraper reaches the other end of the machine, means to start the scraper toward the first named end of the machine from the other end of the machine, a hydraulic speed-varying transmission unit for driving the shaft, a control member regulating the output speed of the unit, means to drive the scraper from the unit, means governed by the position of the scraper and actuating the control member so as to set the unit at a low output speed when the scraper is starting from either end of the machine, to thereafter rapidly accelerate the output speed of the unit, and to rapidly decelerate the output speed of the unit as the scraper approaches either end of the machine.

6. In a silk screen printing machine having a printing table, a scraper, a track guiding said scraper for movement back and forth across the table, an element, means to mount said element for reciprocation, a positive kinematic train interconnecting said scraper and said element, said train including a motion reducing mechanism whereby said element duplicates in miniature the movement of the scraper, a reversible electric motor driving said scraper, switches actuated by said element for reversing the motor when the scraper reaches the front of the machine and stopping the motor when the scraper reaches the rear of the machine, a starting switch, and means for relatively adjusting the positions of the first named switches and the element in the direction of movement of the scraper.

7. In a silk screen printing machine having a printing table, a scraper, a track guiding said scraper for movement back and forth across said table, an element, means to mount said element for reciprocation, a positive kinematic train interconnecting said scraper and said element, said train including a motion reducing mechanism whereby said element duplicates in miniature the movement of the scraper, a reversible electric motor, a hydraulic speed-varying transmission unit driven by the electric motor, a control member regulating the output speed of the unit, means to drive the scraper from the unit, a control circuit for said electric motor, a starting switch, switches for governing the operation of said motor, said last named switches and said control member being so disposed for actuation by said element that upon actuation of

70

12

said starting switch said scraper will start at slow speed from the rear of the machine, rapidly accelerate, subsequently rapidly decelerate as it approaches the front of the machine, reverse at the front of the machine, slowly start to the rear of the machine, rapidly accelerate, subsequently rapidly decelerate as it approaches the rear of the machine, and finally stop as it reaches the rear of the machine, and means for relatively adjusting the positions of the last named switches and the element in the direction of movement of the scraper.

8. In a silk screen printing machine having a printing table, a scraper, a track guiding said scraper for movement back and forth across said table, a reversible electric motor, a positive kinematic train interconnecting said scraper and said motor, an element, means to mount said element for reciprocation, a motion reducing mechanism driven by a member of said train and actuating said element whereby said element duplicates in miniature the movement of the scraper, a control circuit for said electric motor, a starting switch, and switches for governing the direction of rotation of said motor, said last named switches being actuated by said element in such manner that the scraper upon actuation of the starting switch will start from the rear of the machine, reverse at the front of the machine, and stop at the rear of the machine.

9. In a silk screen printing machine having a printing table, a scraper, a track guiding said scraper for movement back and forth across said table, a reversible electric motor, a positive kinematic train interconnecting said scraper and said motor, a threaded element, a threaded shaft meshing with said threaded element, means to turn said shaft from a member of said train whereby said element duplicates in miniature the movement of the scraper, a control circuit for said electric motor, a starting switch, and switches for governing the direction of rotation of said motor, said last named switches being actuated by said element in such manner that the scraper upon actuation of the starting switch will start from the rear of the machine, reverse at the front of the machine, and stop at the rear of the machine.

10. In a silk screen machine having a printing table, a scraper, a track guiding said scraper for movement back and forth across said table, a rotary shaft, a positive kinematic train interconnecting said shaft and scraper for driving said scraper, and a hydraulic speed-varying transmission unit in said train, said unit including a control member for regulating the output speed of the unit, said control member being disposed for actuation as the scraper approaches the end of its travel to rapidly decelerate the scraper.

11. In a silk screen printing machine having a printing table, a scraper, a track guiding said scraper for movement back and forth across said table, a rotary shaft, a positive kinematic train interconnecting said shaft and scraper for driving the scraper, an element, means to mount said element for reciprocation, a positive kinematic train interconnecting said scraper and said element, said last named train including a motion reducing mechanism whereby said element duplicates in miniature the movement of the scraper, said first named train including a hydraulic speed-varying transmission unit having a control member regulating the output speed of the unit, said member being so disposed for

actuation by said element that as the scraper approaches an end of the machine the element will engage the member and rapidly decelerate the output speed of the unit.

12. In a silk screen printing machine having a printing table, a scraper, a track guiding said scraper for movement back and forth across said table, an element, means to mount said element for reciprocation, a positive kinematic train interconnecting said scraper and said element, said train including a motion reducing mechanism whereby said element duplicates in miniature the movement of the scraper, a reversible electric motor, a hydraulic speed-varying transmission unit driven by the electric motor, a control member regulating the output speed of the unit, means to drive the scraper from the unit, a control circuit for said electric motor, a starting switch, switches for governing the operation of said motor, and means adjustably mounted on said element for actuating said last named switches and said control member so that upon actuation of said starting switch said scraper will start at slow speed from the rear of the machine, rapidly accelerate, subsequently rapidly decelerate as it approaches the front of the machine, reverse at the front of the machine, slowly start to the rear of the machine, rapidly accelerate, subsequently rapidly decelerate as it approaches the rear of the machine, and finally stop as it reaches the rear of the machine.

13. In a silk screen printing machine having a printing table, a scraper, a track guiding said scraper for movement back and forth across said table, an element, means to mount said element for reciprocation, a positive kinematic train interconnecting said scraper and said element, said train including a motion reducing mechanism whereby said element duplicates in miniature the movement of the scraper, a reversible electric motor, a hydraulic speed-varying transmission unit driven by the electric motor, a control member regulating the output speed of the unit, means to drive the scraper from the unit, a control circuit for said electric motor, a starting switch, switches for governing the operation of said motor, means adjustably mounted on said element for actuating the last named switches so that upon actuation of said starting switch said scraper will be driven from the rear to the front of the machine, reverse, be driven to the rear of the machine and stop, and means adjustably mounted on said element for engaging the control member to rapidly accelerate the output speed of the unit as the scraper starts from the front or rear of the machine and to rapidly decelerate the output speed of the unit as the scraper approaches the front or rear of the machine.

14. In a silk screen printing machine having a printing table, a scraper, a track guiding said scraper for movement back and forth across said table, an element, means to mount said element for reciprocation, a positive kinematic train interconnecting said scraper and said element, said train including a motion reducing mechanism whereby said element duplicates in miniature the movement of the scraper, a reversible electric motor, a control circuit for said electric motor, a starting switch, switches for governing the operation of said motor, and means adjustably mounted on said element for actuating said last named switches so that upon actuation of said starting switch said scraper will start from the rear of the machine, reverse at the front of the

machine and stop at the rear of the machine.

15. In a silk screen printing machine having a printing table, a scraper, a track guiding said scraper for movement back and forth across said table, an element, means to mount said element for reciprocation, a positive kinematic train interconnecting said scraper and said element, said train including a motion reducing mechanism whereby said element duplicates in miniature the movement of the scraper, a reversible electric motor, a hydraulic speed-varying transmission unit driven by the electric motor, a control member regulating the output speed of the unit, means to drive the scraper from the unit, means to control the motor so as to start the scraper from the rear of the machine, reverse it at the front of the machine and stop it at the rear of the machine, and means adjustably mounted on said element for engaging the control member so as to rapidly accelerate the output speed of the unit as the scraper starts from the front or rear of the machine and to rapidly decelerate the output speed of the unit as the scraper approaches the front or rear of the machine.

16. In a silk screen printing machine having a printing table, a scraper, a pair of tracks at opposite sides of said scraper and extending from the front to the rear of the machine, means supporting the ends of said scraper and riding on said tracks, means to pivotally mount said tracks for oscillation about a common horizontal axis at the rear of the machine, a pair of elongated flexible members, a rotary member at the front and rear of each track about which the elongated members are trained, means to connect said elongated members to the opposite ends of the scraper supporting means for driving the same, a second rotary member at the rear of each track, said second rotary members being mounted for rotation about said common horizontal axis, means to rotate the first named rear rotary members from the last named rotary members, and means to turn said last named rotary members selectively in one direction or another, said last named means including a countershaft, means operatively connecting said countershaft to said last named pair of rotary members, a threaded member on said shaft, a threaded element meshing with said threaded member so as to duplicate in miniature the movement of the scraper, a hydraulic speed-varying transmission unit including a fluid motor and a variable delivery fluid pump, an electric motor driving said pump, a control member for said pump, the regulation of which will change the output speed of the unit, switches for controlling the motor, and means movable by said element for operating said switches and said control member.

17. A combination as set forth in claim 16 wherein the switches include a stop switch and a reverse switch, and wherein the element includes a first component adjustably mounted thereon for engaging the stop switch when the scraper reaches a selected point adjacent the rear of the machine and a second component adjustably mounted thereon for engaging the reverse switch when the scraper reaches a selected point adjacent the front of the machine.

18. A combination as set forth in claim 17 wherein the element includes a third component mounted therefor engaging the control member to decelerate the output speed of the unit when the scraper approaches the selected points adjacent the front or rear of the machine.

19. A combination as set forth in claim 16

wherein the switches include a stop switch and a reverse switch, wherein the element includes a first component adjustably mounted thereon for engaging the stop switch when the scraper reaches a selected point adjacent the rear of the machine and a second component adjustably mounted thereon for engaging the reverse switch when the scraper reaches a selected point adjacent the front of the machine, and wherein the element includes a third component mounted thereon for engaging the control member to decelerate the output speed of the unit when the scraper approaches the selected points adjacent the front or rear of the machine.

20. A combination as set forth in claim 16 wherein the switches include a stop switch and a reverse switch, and wherein the element constitutes a yoke including two arms each of which adjustably supports a pair of studs, one of said adjustable studs on one of said arms being disposed to engage the stop switch when the scraper reaches a selected point adjacent the rear of the machine, one of said adjustable studs on the other arm being disposed to engage the reverse switch when the scraper reaches a selected point adjacent the front of the machine, the other adjustable studs on said arms being disposed to engage the control member just before the aforementioned studs engage the stop or reverse switches so as to decelerate the output speed of the unit. 30

21. In a silk screen printing machine having a printing table, a scraper, a track guiding said scraper for movement back and forth across said table, said track including two pairs of hollow tubes disposed at opposite ends of the scraper, each pair of tubes including an upper tube and a lower tube, a sprocket rotatably mounted at the rear of each pair of tubes, a sprocket rotatably mounted at the front of each pair of tubes, means to reversibly rotate said rear sprockets, a pair of chains one trained about the sprockets at each end of the scraper, the upper flight of each chain being disposed in an upper tube and the lower flight of each chain being disposed in a lower tube, and means connecting one flight of each chain with the associated end of the scraper.

JOHN B. THOMAS.
